UNITED STATES PATENT OFFICE.

CHARLES SWINSCOE, OF CLINTON, MASSACHUSETTS, ASSIGNOR TO CLINTON WIRE CLOTH COMPANY, OF CLINTON, MASSACHUSETTS.

WELDED FABRIC.

949,668.

Specification of Letters Patent. Patented Feb. 15, 1910.

Application filed May 23, 1907. Serial No. 375,263.

To all whom it may concern:

Be it known that I, CHARLES SWINSCOE, of Clinton, in the county of Worcester and State of Massachusetts, have invented certain new and useful Improvements in Welded Fabric, of which the following is a specification.

This invention relates to a new and improved welded fabric.

Figure 1 is a view showing a section of my improved fabric, showing one way in which it may be arranged in a trough or form adapted to receive the ingredients of artificial stone. Fig. 2 is a plan view of a section of the fabric. Fig. 3 is a view showing the fabric arranged in the form of a shell. Fig. 4 is a sectional view showing the fabric in the artificial stone.

1 represents a series of metallic strand members. These may be wire or rods or bars of any desired size and cross section.

2 represents a series of stay members arranged upon the strand members and electrically welded to the strand members at points of intersection. The metallic stay members 2, may be of wire, rods or bars of any desired size and cross-section. These stay members as shown, are positioned upon the strand members in an uneven manner so that they occupy varying angles with rela-

tion to each other, some of the stay members being at right angles to the strand members and others at varying angles, less or greater than a right angle.

In Fig. 4 the binder is shown embedded in 35 artificial stone 10.

Having thus explained the nature of my invention and described a way of constructing and using the same, though without attempting to set forth all of the forms in 40 which it may be made, or all of the modes of its use, what I claim and desire to secure by Letters Patent is:—

As a new article of manufacture, a welded fabric comprising a plurality of metallic 45 strand members and a plurality of sets of stay members, the stay members in each set being arranged at an angle to each other, the stay members of each set being oppositely positioned upon the strand members 50 from the stay members of the succeeding set, and all of the said stay members being arranged on the same side of the strand members.

In testimony whereof I have affixed my 55 signature, in presence of two witnesses.

CHARLES SWINSCOE.
